UNITED STATES PATENT OFFICE

149,964

DESIGN FOR A HAIRBRUSH

Peter Muller-Munk, Pittsburgh, Pa., assignor to Pro-phy-lac-tic Brush Company, Northhamton, Mass., a corporation of Delaware

Application August 9, 1947, Serial No. 140,794

Term of patent 7 years

(Cl. D86—10)

To all whom it may concern:

Be it known that I, Peter Muller-Munk, a citizen of the United States of America, and a resident of Pittsburgh, county of Allegheny, Commonwealth of Pennsylvania, have invented a new, original, and ornamental Design for a Hairbrush, of which the following is a specification, reference being had to the accompanying drawing, forming part thereof.

In the drawing:

Fig. 1 is a view in side elevation of a hairbrush showing my new design.

Fig. 2 is a top plan view thereof.

Fig. 3 is a section taken on line 3—3 of Fig. 2.
My design is characterized by a brush back and handle of contrasting colors, as shown.

I claim:

The ornamental design for a hairbrush, substantially as shown and described.

PETER MULLER-MUNK.
